UNITED STATES PATENT OFFICE.

EDWARD M. BRENNAN, OF SPRINGFIELD, OHIO, AND ERWIN H. HUSSEY, OF MINNEAPOLIS, MINNESOTA, ASSIGNEES TO THE BAUER BROTHERS COMPANY, OF SPRINGFIELD, OHIO, A CORPORATION OF OHIO.

FEEDING DEVICE.

Application filed March 8, 1928. Serial No. 260,136.

This invention relates to feeding devices particularly adapted for feeding material, together with a supply of fluid such as water, or water and steam, to apparatus such as attrition mills.

The object of the invention is to provide an improved arrangement for introducing water, or water and steam, to the feeding mechanism so that the water, or water and steam, are intimately mixed with the material before being introduced into the mill.

In the accompanying drawings:

Fig. 1 is a plan view of feeding device embodying the improvements.

Fig. 2 is a view partly in side elevation and partly in longitudinal section, the section being on the line 2—2 of Fig. 1.

Fig. 3 is a vertical section, the section being on the line 3—3 of Fig. 2.

Fig. 4 is a side elevation of one of the nozzles for injecting water or steam, or both.

Referring to the drawings, 1 is a casing open at the top and bottom and mounted upon a suitable hollow pedestal 2. A horizontal longitudinally extending shaft 3 is mounted in suitable bearings 4 carried in the outer end of hollow bosses 5 formed integrally with the end walls of the casing 1, each of these bosses also having a bushing 6 or sleeve of lignum vitae surrounding and cooperating with a spiral groove 7 in the shaft to prevent leakage of the water. Secured to the reduced portion of one end of the shaft is a worm wheel 8 meshing with a worm 9 on one end of a transversely arranged horizontal shaft 10, the other end of which has a power transmission device, such as 11 to which power is transmitted from any suitable source (not shown). Secured to the shaft 3 are the hubs of bell-shaped webs 12 to which are fastened a drum 13 having feeding devices such as teeth or projections 14. An adjustable cut-off plate 15 is secured to the casing 1 to assist in regulating the feed of the material.

Arranged in the forward side wall and also in the rear side walls is a nozzle consisting of an elongated hollow body 16 which has on its outer side a threaded nipple 17 to which may be connected a suitable supply line (not shown) for water, or water and steam. The inner side wall of this hollow body is provided with a series of jet open-

ings 18 which extend the entire length of the interior portion of the casing. These 55 hollow bodies fit in elongated slots in the walls of the casing and are provided with flanges 19 by which they are bolted to the casing walls.

The feeding drum is offset or placed at one 60 side of the longitudinal center of the casing so that the feeding teeth or projections 14 closely hug the walls of the casing on the upside but are quite well removed therefrom on the down side to improve the feed 65 action.

To prevent air binding below the feeding mechanism, the pedestal 2 is provided with air inlets, preferably covered by screens 21, these inlets being formed by enlarging the 70 end walls of the pedestal. To prevent the water flowing with the material from splashing out through the air inlet openings, the walls of the pedestal are so formed as to provide depending lips 22 which project 75 downwardly and form inner walls for the air inlet openings so as to deflect the liquid downwardly at the points of the air openings.

By this arrangement it will be seen that 80 effective means are furnished for supplying an ample amount of water, or water and steam, to the material in such a way that they will be thoroughly mixed with the material before introducing into the mill.

Having thus described our invention, we claim:

1. In a feeding device of the character described, a casing having an upper inlet opening and a lower discharge opening, a 90 conduit leading from the discharge opening in said casing, feeding mechanism for material located in said casing and means for ejecting fluid into said casing, said conduit being provided with an air inlet opening 95 formed by extending the entrance thereof above the inner wall to prevent splashing of the fluid therethrough.

2. In a feeding device of the character described, a casing having inlet and discharge 100 openings for material, feeding mechanism therein for said material, an elongated nozzle for discharging fluid into said casing, said nozzle being confined in the wall of said casing so as to be removed from the path of 105 the material passing through the casing.

3. In a feeding mechanism of the character described, a casing, a rotatable feeding device in said casing, said device being arranged to closely hug at least one wall of said casing at one point in the rotation thereof, and an elongated nozzle confined in the wall of said casing at that point for

discharging fluid into said casing so that said nozzle will be out of the path of material passing through the casing. ¹⁰

In testimony whereof, we have hereunto set our hands this 6th day of March, 1928.

EDWARD M. BRENNAN.
ERWIN H. HUSSEY.
